UNITED STATES PATENT OFFICE.

ALEXANDER C. RANKIN, OF CHICAGO, ILLINOIS.

COMBINED BRACE AND SUSPENSORY.

SPECIFICATION forming part of Letters Patent No. 762,555, dated June 14, 1904.

Application filed August 27, 1903. Serial No. 171,000. (No model.)

To all whom it may concern:

Be it known that I, ALEXANDER C. RANKIN, a citizen of the United States, residing at Chicago, in the county of Cook, State of Illinois, 5 have invented certain new and useful Improvements in a Combined Brace and Suspensory, of which the following is a specification, reference being had therein to the accompanying drawings.

10 This invention relates to a suspensory garment, and particularly to an undergarment provided with a suspensory and abdominal support thereon.

The invention has for an object to provide 15 a suspensory permanently attached to a pair of drawers, so as to be held thereby in proper position for comfortably and properly supporting the parts.

20 A further object of the invention is to provide an improved form of abdominal support at the upper portion of the drawers adapted to be connected with the undershirt or body garment by elastic connections by which a perfect freedom of movement is permitted 25 without displacing the parts from their proper positions.

Other and further objects and advantages of the invention will be hereinafter set forth and the novel features thereof defined by the 30 appended claims.

In the drawings, Figure 1 is a front elevation with the lower portion of the shirt broken away, and Fig. 2 is a similar view of the rear of the garment.

35 Like letters of reference refer to like parts in both figures of the drawings.

The letter A designates a pair of drawers, which may be of any desired material or construction and from which the usual fly portion 40 has been removed, and a suspensory bag or sack A', suitably gathered at its free edge A², is secured by means of a non-elastic tape A³, extending about the front opening of the drawers. This permits the bag or sack being 45 held in a fixed position and adapted to support the penis and testicles. From the bottom of the bag A' a non-elastic strip A⁴ extends beneath the crotch of the garment and is connected at its upper end A⁵ with a non- 50 elastic part at the back thereof.

When found desirable, an abdominal brace B may be applied to the upper portion of the drawers above the suspensory, and is adapted to fit the wearer about the waist and above the hip-bones. This brace is formed of two 55 sections slightly overlapped at their front and rear points of juncture and secured together at the front by any suitable fastenings—for instance, hooks and eyes B', as shown in Fig. 1. This portion of the brace is also stiffened and strengthened by means of non-elastic strips B² at their upper and lower edges and intersecting laterally-extending strips B³. In order to adjust the brace snugly to the body of the wearer, a series of adjusting-strips B⁴ 60 are provided at the rear of the garment and secured together by means of buckles B⁵, as shown.

For the purpose of supporting the drawers carrying the abdominal support and suspensory without direct pressure upon the waist or hips of the wearer the shirt or body garment C is provided at its upper portion with non-elastic strips C², for instance, extending from the front at opposite sides of the neck-opening and joined together at the rear of the neckband, as shown at C², from which an extension C³ extends downward centrally at the back of the garment. All of these strips are secured to the shirt, so that they may be 70 laundered therewith, and are provided at their free ends with loops or openings through which elastic connecting-cords C⁴ may pass. These cords are threaded through the loops and attached to the drawers in any desired 75 manner—for instance, by means of a loop C⁵ at one end thereof engaged with any ordinary construction of hook, as shown at C⁶, which method of adjustment permits a very quick and convenient disengagement of the garments from each other.

In the use of the garment it will be seen that the method of attaching the suspensory at the fly of the drawers by means of the non-elastic strips prevents the bagging downwardly and outwardly of the suspensory bag or sack, and thus effects a support for the testicles when stooping or in athletic exercise. The strips hold the suspensory at its outer edges close to the body of the wearer by means 90 95 100

of their attachment and prevent any side shifting, while the bottom strip extending beneath the crotch also prevents any upward movement of the suspensory. These side strips 5 also support the suspensory at sufficient distance from the scrotum to prevent any contact therewith or with the testicles when the legs are crossed and also hold the sack far enough to one side to prevent working into 10 the groin and coming in contact with the spermatic cord. This arrangement forms a suspensory more in the character of a hammock-support than a sack and permits the formation of a large opening around the penis, 15 thus preventing overheating or chafing thereof in the event of exercise in warm weather. The abdominal support, in connection with the supporting means, protects the back and kidneys, giving a perfect support to the stomach, 20 while by means of the elastic supporting-cords it obviates the necessity of any stay-ribs or elastic cloth in the support, so that the garment can be readily laundered without detriment to the material thereof. This support, 25 held by cords which are removably connected to non-elastic strips carried by the shirt, is readily connected and disconnected therefrom when desired. These cords obviate the use of buckles or other metallic parts liable to chafe 30 or contact with the body in the use of the garment. If desired, these cords may be of different strength or size—for instance, the two in front of smaller size than the one at the rear.

35 The garment formed by the foregoing construction is adapted to support the three materially weak points of the body—namely, the back and kidneys, the stomach, and the testicles—without being complicated or uncomfortable, and is of such simple construction that the garments can be readily laundered, while the connecting means can be quickly and conveniently applied by any person.

40 It will be obvious that changes may be made in the details of construction and configuration without departing from the spirit of the invention as defined by the appended claims.

Having described my invention and set forth its merits, what I claim, and desire to secure 45 by Letters Patent, is—

50 1. In a suspensory garment, a drawers having the fly portion removed, a sack or bag

disposed to fill the lower part of the fly portion thereof, a non-elastic strip extending about the fly portion and connected edge of 55 the sack, and a non-elastic strip secured to the drawers and extending from the lower connected portion of the sack upward through the crotch of the garment to the back thereof.

2. In a suspensory garment, a drawers, a 60 sack or bag disposed at the fly portion thereof, a non-elastic strip extending about the connected edge of said sack, a non-elastic strip extending from the lower portion of the sack upward through the crotch of the garment to 65 the back thereof, an abdominal support disposed at the upper portion of the drawers above said sack or bag, a shirt or body garment, and elastic means connecting said drawers to 70 said shirt.

3. In a suspensory garment, a drawers, a sack or bag disposed at the fly portion thereof, a non-elastic strip extending about the connected edge of said sack, a non-elastic strip extending from the lower portion of the sack 75 upward through the crotch of the garment to the back thereof, an abdominal support disposed at the upper portion of the drawers above said sack or bag, a shirt or body garment, elastic means connecting said drawers 80 to said shirt, and non-elastic strips permanently secured to said shirt and provided at their free ends with loops to receive said elastic attaching means.

4. In a garment of the class described, a 85 drawers, an abdominal brace permanently applied to the upper portion thereof and formed in separate sections, a series of adjusting buckles and strips at the rear point of connections of said sections, a series of detachable connecting devices at the front connection of said sections in alinement with the fly-opening of the drawers, a shirt having non-elastic strips secured thereto and provided with loops at their free ends, attaching-hooks 90 upon each section of said brace, and elastic cords threaded through said loops and removably connected to said hooks.

In testimony whereof I affix my signature in presence of two witnesses.

ALEXANDER C. RANKIN.
